Specification for Design.

Patented May 5, 1914.

Application filed March 17, 1913. Serial No. 755,038. Term of patent 14 years.

To all whom it may concern:

Be it known that I, ELMER E. POOLE, a citizen of the United States, residing at Boston, in the county of Suffolk and State of Massachusetts, have invented a new, original, and ornamental Design for a Combined Tail-Light and Sign-Plate Holder, of which the following is a specification, reference being had to the accompanying drawings, forming a part thereof.

In the drawings Figure 1 is a perspective view of a combined tail light and sign plate holder showing my new design. Fig. 2 is

an end view and Fig. 3 is a section on line 3—3 of Fig. 1.

The dotted lines indicating the sign plate form no part of the design but are simply placed on the drawing to indicate the location of the sign plate.

I claim:

The ornamental design for a combined tail-light and sign plate holder as shown.

ELMER E. POOLE.
